VENDING STORAGE BIN

John Schendorf, Metuchen, N.J., and Irving Goldbert, Mountainside, N.J. (231 North Ave., Garwood, N.J. 07027); said Schendorf assignor to said Goldbert
Filed Feb. 25, 1966, Ser. No. 530,114
6 Claims. (Cl. 221—242)

ABSTRACT OF THE DISCLOSURE

Vending storage bin having adjustable side plates pivoted on a transverse rod and slideable longitudinally therealong, and a notched transverse member spaced from the rod, so that a side plate can swing out of one notch, slide along the rod, and swing into another notch.

This invention relates to vending storage bins, and more particularly to such bins for articles in a vending machine released by a coin controlled mechanism.

Vending machines are being made and are already in use for vending articles such as cigarette packs, which are of relatively small dimensions. Such machines have a series of parallel mechanisms each comprising a dispensing plunger, a storage bin above the plunger, a supply rack at the bottom of the storage bin, and a pusher driven along the supply rack by the plunger.

It has become desirable to adapt one or more of such mechanisms in the series to dispense larger articles such as packs of cigars, which are wider or longer, or both, than the cigarette packs of the remaining mechanisms of the series.

The main object of the present invention is directed to the storage bins, to make them adjustable to receive and deliver to such mechanisms the packages of larger or smaller, wider or narrower, sizes.

In our development, we have adapted a short stroke plunger mechanism to provide a longer stroke for the delivery pusher. It is therefore a more specific object of the present invention to adapt the storage bins for vending machines to receive larger size packages, for delivery therefrom by said longer stroke pusher.

According to the present invention, at least one of the storage bin side plates is mounted on a transverse pivotal axis and movable therealong, and a transverse member is spaced from the pivotal axis and has selective abutments for locating the side plate nearer to or farther from the supply rack to receive narrower or wider articles.

Preferably the supply racks comprise platforms equally transversely spaced in fixed relation along a common support. Preferably the transverse member has upper and lower flanges extending toward each side plate, with notches in the edges forming said selective abutments. Preferably the side plate is provided with a strip near one edge of the side plate having an angle flange, and a pin and slot connection between the strip and plate for adjusting said angle flange to receive longer or shorter articles.

In the drawings:

FIGURE 1 is a section through a vending machine provided with storage bins according to the preferred embodiment of the present invention, as taken along the line 1—1 of FIGURE 2;

FIGURE 2 is a vertical section taken along the line 2—2 of FIG. 1;

FIGURE 3 is a perspective view of one adjustable bin side plate;

FIGURE 4 is a perspective view of a complementary adjustable bin side plate; and

FIGURE 5 is a perspective view of the locking device for the adjusted side plates.

As shown in FIGURE 1, the machine has a series of

2

parallel dispensing mechanisms operated by respective plungers 10. The machine also has storage bin supply racks comprising platforms 12 equally transversely spaced in fixed relation along a common support 14.

As shown in FIGURE 2, each plunger 10 actuates a lever 16 connected to a depending portion 18 of a pusher 20 to drive it for a delivery stroke. The portions 18 depend through respective slots 22 in the support 14.

The storage bins have parallel side plates 24 and 26 movable toward and away from each other to form wider or narrower bins to receive packages of different widths shown as A, B, C, and G, H, I. The side plates between these two groups are arbitrarily removed to show the pushers 20 operating along the slots 22 between the platforms 12.

The side plates 24 and 26 are mounted on a transverse rod 28, at least one of said side plates being pivoted thereon and movable therealong. The rod 28 is supported at its ends by transverse end portions 30 of the machine casing at the rear thereof.

Spaced from the rod 28, preferably therebelow is a transverse member 32 having spaced abutments 34 for locating the side plates in selected width positions. In the form shown, the member 32 is channel shaped, having flanges 36 and 38 with spaced notches therein forming the abutments 34.

Both side plates have lateral vertical flanges 40 at the back thereof as stops for the back ends of the articles, and rearwardly extending lower vertical flanges 42 for selectively engaging the notches 34.

For locking the movable side plates in selected position, a clip is provided, as shown in FIGURE 5. This clip has a vertical strip 45 with a top flange 46 having notches 48 complementary to the notches 34. This clip also has a bottom flange 50 with a bolt hole 49 receiving a bolt 51 to secure it to the top of the platform 12. The bottom flange 50 has a depending tongue 52 received in a centering slot 53 in the platform.

At least one of the side plates, 24 as shown has an angle flange 54 with a pin and slot connection to the side plate. In FIGURE 4 the flange 54 has a pivot 56 at the top, and spaced slots therebelow. The top slot 59 receives a rivet 60, and the bottom slot 61 receives a set screw 62.

What is claimed is:

1. In a dispensing machine having parallel mechanisms each comprising a dispensing plunger, a storage bin having parallel side plates, a supply rack at the bottom of said storage bin, and a pusher driven along said supply rack by said plunger, means for mounting at least one of said side plates at substantially a mid portion of the back thereof on a transverse pivotal axis in the back of said machine above the path of said pusher and below the tops of said side plates, said plate being perpendicular to and slideable along said pivotal axis toward and away from the path of said pusher and a transverse member in the back of the machine and spaced below said pivotal axis and having transversely spaced abutments, said mounting permitting said movable side plate to swing out of engagement with one abutment, move along said axis to a second abutment, and swing back into engagement with said second abutment for selectively locating said movable side plate.

2. Dispensing machine as claimed in claim 1, in which said supply racks comprise platforms extending in a direction from front to back of said machine and equally spaced transversely in fixed relation along a common support with the path of said pusher therebetween and therebelow and parallel thereto.

3. Dispensing machine as claimed in claim 1, in combination with a removable member in front of said movable side plate having corresponding abutments for locking said movable side plate in selected position.

4. Dispensing machine as claimed in claim 1, in which said transverse axis on which said movable plate is pivoted is formed by a transverse rod.

5. A dispensing machine having a series of parallel mechanisms each comprising a dispensing plunger 10. 5 a storage bin having parallel side plates 24 and 26, and a supply rack at the bottom of said storage bin, said supply racks comprising platforms 12 equally transversely spaced in fixed relation along a common support 14 and rising thereabove, 10 a pusher 20 driven by said plunger along a slot 22 in said common support 14 between an adjacent pair of said platforms 12, a transverse rod 28 in the back of said machine above the top of said platforms 12 and below the tops of 15 said side plates 24 and 26, a mid portion of at least one of said side plates 24 and 26 being pivoted on said rod 28 perpendicular thereto and slideable therealong toward or away from said pusher slots 22, and a transverse flange 36 or 38 in the back of the machine 20 and spaced below said rod and having notches 34

10

15

20

spaced therealong to selectively receive the back of said side plate 24 or 26.

6. Dispensing machine as claimed in claim 5, in combination with a complementary flange 46 having correspondingly spaced notches 48 to selectively receive the front of the selected side plate, and removably secured 49, 51 to the top of the front portion of one of said platforms 12 to secure the selected side plate 24 or 26 in position.
